**KEY AND COIN LOCK FOR CLEANING
DEPOSITORY**

Robert K. Hensley, Jr., Hillcrest Heights, Md.
(5915 Farmer Drive SE, Washington 22, D.C.)
Filed Mar. 20, 1959, Ser. No. 800,825
9 Claims. (Cl. 194—54)

The present invention generally relates to an improved key and coin lock that is especially adapted for cleaning depositories but which may be used for other similar purposes having similar problems that must be solved.

The primary object of the present invention is to provide a key and coin lock device for locking and releasing a closure member such as is used on lockers or the like for dry cleaning, laundry or the like so that a customer upon payment of an initial fixed sum may deposit cleaning in the locker or depository and take with him the key for that depository with only a serviceman then being able to open the depository for removal of the soiled cleaning and replacement thereof after cleaning, the serviceman then conditioning or setting the mechanism for enabling the customer, by depositing any indicated monetary sum, to regain the cleaned clothes by using the key that he originally took with him, the key then being retained in the lock after the customer has obtained his clean clothes therefrom with the lock mechanism being automatically conditioned for subsequent deposit of a fixed sum by another customer.

Another important feature of the present invention is to provide an arrangement in which a portion of the lock mechanism including the key receiving lock may be removed and orientated in other lockers or depositories in a group or bank of lockers or depositories thereby enabling more effective use of the lockers or depositories with the customer only relying upon indicating means on his key and on the movable part of the lock mechanism which may conveniently be numerical indicia for associating the proper key with the proper lock with this function being effectively carried out by providing in the lock mechanism an aperture for engagement over the garment hanger upon which the cleaning is normally deposited so that the cleaning and the lock mechanism which is removable will remain together at all times from the time the serviceman picks up the dirty clothes until he deposits the clean clothes at which time he inserts the lock mechanism that was carried with the clothes into the closure member operating mechanism that remains with the depository with all of the lock mechanisms being different and with all of the closure latching and operating mechanisms being the same.

Yet another object of the present invention is to provide a key and coin lock arrangement which is substantially foolproof in operation, simple in structure in that it contains all mechanical parts and requires no electrical components, trouble free in operation and relatively easy to maintain.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of a locker or depository with the key and coin lock mechanism of the present invention incorporated therein;

FIGURE 2 is a plan view of the key and coin lock mechanism with the cover thereof removed illustrating generally the structural layout of component parts;

FIGURE 3 is a sectional view taken substantially upon a plane passing along section line 3—3 of FIGURE 2

2

but with the top in position and illustrating the components of the mechanism in elevation;

FIGURE 4 is a sectional view taken substantially upon a plane passing along section line 4—4 of FIGURE 2 illustrating further structural details and orientations of component parts;

FIGURE 5 is a sectional view taken substantially upon a plane passing along section line 5—5 of FIGURE 2 illustrating the relationship of the slide bolt and release lever which senses the presence or absence of coins deposited into the coin holder;

FIGURE 6 is a detailed elevational view of the lower end of the coin holder including the abutment therefor and the lower end of the vertical rod which operates the coin release lever;

FIGURE 7 is a detailed sectional view taken substantially upon a plane passing along section line 7—7 of FIGURE 2;

FIGURE 8 is a detailed sectional view taken substantially upon a plane passing along section line 8—8 of FIGURE 4 illustrating the details of the indicating mechanism in the top of the housing;

FIGURE 9 is a longitudinal, sectional view taken substantially upon a plane passing along section line 9—9 of FIGURE 2 illustrating the structural details of the sliding bolt and the latch mechanism for the closure member;

FIGURE 10 is a partial plan view of the mechanism illustrating the orientation of components after a coin has been deposited and the bolt is moved inwardly a portion of its stroke such as would occur when a customer has deposited a coin preparatory to depositing soiled clothes for cleaning;

FIGURE 11 is a plan view illustrating the structure after the bolt has been pushed completely inwardly and then withdrawn and the lock mechanism actuated to lock the bolt to prevent inward movement thereof with the key being taken by the customer with this condition being the condition in which the serviceman finds the lock mechanism when he takes out the soiled clothes;

FIGURE 12 is a plan view similar to FIGURE 11 but with the mechanism conditioned by the serviceman so that by deposit of a predetermined quantity of coins and insertion of the customer's key, the lock bolt may be pushed inwardly and the clothes removed with the lock arm automatically returning to an unlocked position and indicating that the locker is vacant and ready for service;

FIGURE 13 is a plan view similar to FIGURE 10 but showing the condition after the bolt has been pushed all the way in from the position of FIGURE 12;

FIGURE 14 is a perspective view of the slide bolt;

FIGURE 15 is a perspective view of the removable coin receiving mechanism showing the adjustable slide and the coin release lever;

FIGURE 16 is a plan view of the indicating window when the indicator shows that the locker is vacant; and

FIGURE 17 is a plan view of the indicating window when the window indicates to the customer the number of coins necessary for retrieving the cleaned garments.

Referring now specifically to the drawings, the numeral 10 generally designates the coin and key lock mechanism of the present invention for use with a locker or depository generally designated by the numeral 12 which is of a relatively tall, narrow and deep construction and which may be arranged in side-by-side relation into a bank or group such as would occur in various public places and in buildings such as parking buildings or the like. The hollow housing or casing defining the locker 12 is designated by the numeral 14 and is provided with a sliding front closure member 16 having a suitable handle or the like 18 thereon for raising the closure member 18 to a closed position. The lock mechanism 10 may be

in the form of an attachment or may be built into the locker 12. It is noted that the front wall below the lock mechanism is inwardly tapered as designated by the numeral 20 with the lock mechanism including side walls 22, a front wall 24, a rear wall 28 and a removable top, cover or lid 30. The rear wall 28 overlaps the lower edge of the closure member 16 and has a bracket 32 therein carrying a latch member 34 for pivotal movement about a horizontal axis pin 36 and which includes a keeper or projection 38 which engages an opening 40 in the lower end of the closure member 16 and which also extends through an opening 42 in the rear wall 28. The lower end of the pivotal latch 34 is provided with an abutment 44 and a suitable spring is provided for urging the latch member 34 about the pivot pin 36 for registering the projection 38 with the aperture 40 and a stop member 46 is provided for limiting movement of the latch member 34 in this direction. Thus, when the abutment 44 is engaged and moved towards the rear wall 28, the projection 38 will be withdrawn from the aperture 40 in the closure member 16 and the closure member 16 may then be moved downwardly for access into the interior of the locker.

The top or cover 30 is provided with a depending peripheral reinforcing rib 48 which engages the inner surface of the walls of the lock housing thus positively locating the cover or lid. Adjacent the outer edge of the cover 30 there is provided a key operated lock mechanism 50 which has a horizontal swingable lock arm 52 for engagement under a keeper 54 rigid with the front wall 24 for releasably holding the cover in position. The inner edge of the cover 30 is provided with a pair of downwardly offset projections for engagement with corresponding notches in the rear wall 28 for positive alignment and locking engagement of the cover with the housing.

The cover 30 is also provided with a laterally extending and upwardly inclined coin chute 56 having instructive indicia 58 thereon for instructing customers to deposit coins in the outer end thereof. The coins roll down the incline of the chute 56 and drop downwardly into a coin receiving means generally designated by the numeral 60 and which includes a pair of vertically elongated strips 62 and 64 both of which are provided with longitudinally extending facing grooves 66 on the inner edges thereof and projecting ribs 68 on the outer edge thereof. The grooves 66 are in alignment with an opening 70 in a transverse member 72 interconnecting the upper ends of the strip members 62 and 64 and underlying the discharge end of the chute 56 whereby coins will be directed downwardly between the strip members 62 and 64. The opening 70 may be slightly tapered and funnel shaped for guiding coins into the grooves or channels 66 between the strips 62 and 64. One wall of the groove 66 in the member 64 is cut away or recessed as indicated by the numeral 74 for permitting coins smaller than the designated diametrical size to fall laterally outwardly of the coin mechanism due to normal lateral movement of the coin during downward movement thereof thus rendering the device incapable of operation except when the proper diametrical size coin is used such as a quarter.

The lower ends of the strip members 62 and 64 are interconnected by a base member 76 and the strip member 62 is provided with a plurality of longitudinally spaced sockets 78 each having numerical indicia 80 adjacent thereto for indicating the number of coins that will be received within the coin receiving means when the lock mechanism will operate which the serviceman will set when he deposits the cleaned garments in the depository.

The means for setting the number of coins include a slide mechanism generally designated by the numeral 82 which includes a block 84 on each side of the strips 62 and 64 with a pair of lugs 86 mounting a spring urged catch 88 thereon which has a rounded plunger or pin

for engagement selectively in one of the sockets 78. The other of the blocks 84 is provided with a coin release lever 90 pivoted thereon by pivot pin 92 with the block also including an upwardly extending lug 94 disposed exteriorly of the lever 90 with a spring 96 being interposed between the lugs 94 and the lever 90 for urging the lever into engagement with the strips 62 and 64. The lever 90 is provided with an inwardly extending projection 98 which extends into the area between the strip members 62 and 64 and which will be disposed normally in the path of movement of coins downwardly into the grooves 66. Thus, the projection 98 will stop the coins when it is disposed as shown in FIGURE 15 with any small coins falling laterally outwardly of the recess 74. If the slide is disposed at another position therein, then the coins will not add up to the proper vertical height and further, the recess 74 will normally cause small coins to drop laterally out of the grooves 66 which are spaced properly for receiving quarters only. The end of the lever 90 remote from the pivot pin 92 is provided with an abutment 100 which lies in the path of movement of means for engaging the coin release lever for pivoting the lever 90 outwardly for moving the projection 98 outwardly between the strip members 62 and 64 thus allowing the coins to drop down through the slide mechanism 82 and be deposited on the block 84 on the strip members 62 and 64. Of course, the coins may be removed by the serviceman when he services the device and for supporting the coin retaining means 60, there is provided a bracket 102 adjacent the upper end of the side wall 22 and a bracket 104 adjacent the bottom of the side wall 22 for receiving the base 76. The bracket 104 as well as the bracket 102 is provided with grooves for receiving the ribs 68 thus holding the coin receiving means in vertical position. For reinforcing the upper bracket 102, there is provided a pivoted strap 106 carried by lug bracket 108 with the end of the strap 106 engaging the outer end of the bracket 102 to prevent movement thereof towards the rear wall 28 thereby rigidifying the upper bracket 102 and being swingable upwardly to an out-of-the-way position to permit removal of the coin receiving means 60 for removing the coins and setting the slide and coin receiving mechanism.

For engaging the abutment 100, there is provided an elongated rod 110 having offset ends 112 journaled in sockets within the brackets 104 and 102 respectively with the rod 110 being arcuately swingable about a vertical axis defined by the offset ends 112 which arcuate swinging movement will bring the rod into engagement with the abutment 100 regardless of the vertical position of the abutment 100 on the coin receiving carrier 60. The upper offset end 112 of the rod 110 extends through the bracket 102 as illustrated in FIGURE 2.

Extending through the front wall 24 is an elongated hollow guide 114 which is rectangular in cross-sectional configuration and which extends for a major part of its length within the interior of the housing defined by the walls with the guide 114 slidably receiving an elongated slide bolt 116 which has an upwardly extending handle or lug 118 on the outer end therof for enabling the same to be pushed inwardly and pulled outwardly. The bolt 116 is of the same cross-sectional configuration as the guide 114. FIGURE 14 illustrates the construction of the bolt which includes an upstanding pin 120 thereon in spaced relation to the inner end thereof together with a screw threaded socket 122 adjacent the pin 120 but slightly nearer the handle forming lug 118 and spaced laterally from the pin 120. One side edge of the bolt 116 is provided with a longitudinally extending groove 124 therein and the top surface of the bolt 116 is provided with a recess 126 extending longitudinally having an upwardly inclined end surface 128 forming a cam for a purpose described hereinafter. The pin 120 is received in an elongated slot 130 in the guide 114 and overlying the threaded socket 122 is a slot 132 which receives

a screw threaded bolt 134 which may be shouldered and which is provided with a sleeve 136 thereon which is rotatable between the headed end 138 of the bolt and the guide 114. Carried by the sleeve 136 is a pivotal arm 140 which extends outwardly and terminates in a generally offset terminal end 142 having an adjustable abutment member 144 on the outer end thereof which will move through the area between the strips 62 and 64 and will feel or sense coins therein. If coins are disposed therein in the path of movement of the abutment 144, the abutment 144 will be held from further movement and upon continued movement of the bolt inwardly, the arm 140 will swing about the bolt 134 until the abutment 144 comes into contact with a projection 143 on the upper bracket 102 in which the upper end 112 of rod 110 pivots whereupon the arm 140 may continue to pivot about the bolt 134 thereby permitting the bolt 116 to slide on inwardly with the inner end thereof coming into engagement with the abutment 44 for releasing the latch 34 in an obvious manner. If no coins were present, then the projection or abutment 144 would engage the outer edge of the projection 143 thus preventing pivotal or swinging movement of the arm 140 and preventing further inward movement of the bolt 116.

The arm 140 is provided with a spring 150 connected to the upstanding pin 120 and to a fastener at the apex of the arm 140 and the offset end 142 for normally urging the arm 140 into perpendicular relation to the sliding bolt 116.

The bolt 116 is also provided with a laterally projecting pin 152 which extends outwardly through a slot 154 in the guide 114 and which will engage the rod 110 when the bolt 116 moves all the way in thereby moving the coin release lever 90 to coin releasing position as illustrated in FIGURE 13. A return spring 156 is connected to pin 152 and a suitable bracket 158 on the front wall 24 thus urging the bolt 116 to its outer position.

The front wall 24 is provided with a removable lock plate 160 which is provided with grooved bottom and side edges 162 for sliding engagement in a notch in the front wall 24 wherein the lock plate 160 may be easily removed by lifting the same and sliding the same vertically upwardly. Mounted in the lock plate 160 is a key operated lock mechanism 164 provided with a key 166 with both the lock plate 160 and key 166 having corresponding indicia such as a corresponding number so that the proper key may be associated with the proper lock mechanism. The lock mechanism is provided with a laterally extending arm 168 which will engage a notch 170 in the bolt 116 through a slot 172 extending vertically through the guide 114. The body 174 which rotatably supports the arm 168 also engages a spring 176 having one end terminally attached to a corner fastener 178 on the arm 168 and the other end connected to a fastener 180 carried by the plate 160 whereby the arm 168 will be urged to a vertical position. The arm 168 is also provided with an inwardly extending pin 182 for a purpose described hereinafter.

Slidably mounted on the side edge of the guide 114 is a slidable bracket 184 having a pivotal tongue 186 connected thereto and spring urged to a position with the free edge thereof lying against the side edge of the guide 114 as illustrated in FIGURE 2 when in this condition. The bracket 184 is provided with inturned lugs 188 engaging longitudinal grooves 190 in the top and bottom walls of the guide 114. The tongue 186 is provided with a projecting pin 192 adapted to extend through a slot in the guide and into the slot 124 in the sliding bolt 116, whereby the bracket 184 will be moved inwardly when the bolt 116 is moved inwardly. Pivotally mounted on bracket 194 is a generally L-shaped latch member 196 mounted by pivot pin 198 and having a flat bowed leaf spring 200 urging one end of the L-shaped latch member 196 downwardly towards the top of the guide. The free end of the latch member 196 is provided with a project-

ing pin 202 which extends downwardly through an opening in the guide 114 and engages the cam recess 126 and particularly the cam end 128 thereof whereby the sliding bolt 116 will cause upward movement of this end of the latch 196 when the bolt 116 moves inwardly thereby causing downward movement of the other end of the latch 196. The other end of the latch 196 is provided with a laterally extending and upturned hook shaped end portion 204 which will engage the lower edge of the tongue 186 thus retaining the tongue 186 in retracted position generally alongside of the latch member 196 substantially as illustrated in FIGURE 12.

The top cover 30 is provided with an indicator opening 206 having a closure member of transparent material 208 which may be glass or plastic. Underlying the indicating opening 206 is a supporting bracket or plate 210 rotatably supporting a disk or wheel 212 which has a portion of the periphery thereof extending beyond the plate with the periphery being knurled or otherwise roughened for permitting rotation of the wheel 212. The wheel 212 is provided with a series of indentations 214 for engagement by a ball detent 216 which is spring urged by spring 218 thus retaining the wheel 212 in rotatably adjusted position. The wheel 212 is provided with a plurality of circumferentially arranged numbers 218 comparable to the numbers 30 appearing on the coin carrying means. Also carried by the bracket 210 is a slidably L-shaped member 220 which has two longitudinally arranged portions with one portion thereof having the word "vacant" printed thereon as indicated by the numeral 222 with the other portion having the word "quarters" as designated by the numeral 224 printed along the bottom edge thereof with the top edge having an opening for revealing the numbers 218 on the disk or wheel 212. The depending flange on the L-shaped indicator 220 is provided with a notch 226 which receives the projecting pin or peg 182 on the lock arm 168 which will automatically move the indicator to the proper indicating position upon proper operation of the device with the serviceman being responsible for rotating the disk 212 so that the proper number of coins will be indicated so that the customer will deposit the proper number of coins when he obtains the cleaned garments. Also, the lock arm is provided with an aperture whereby the lock mechanism may be engaged over the hook of a conventional garment hanger so that the lock mechanism may be taken with the hanger and maintained with the garment while being cleaned.

In operation, the empty locker will be conditioned as illustrated in FIGURE 2. In this condition, the bolt 116 cannot be pushed inwardly since there is no coin to initiate pivotal movement of the arm 140 thus, the abutment 144 will lock with the outer edge of the projection 143. The key of course will be in the lock mechanism. When a quarter is inserted into the coin chute, the lock bolt 116 may be pushed in. It is also pointed out that the key 166 cannot be removed since it is of the type that cannot be removed until the arm is swung to a horizontal position and this cannot occur in view of the position of the bracket 184 and tongue 186. Upon inward movement of the lock bolt 116 which can occur after a quarter has been deposited, the arm 140 is swung rearwardly as indicated in FIGURE 10 and at the same time the coin release mechanism or lever has released the coin and the closure door has been released. Also, note that the pin 192 has engaged with the slot 124 and moved the bracket 184 inwardly out of the path of movement of the lock arm whereby the lock arm may engage the notch 170 in the bolt 116 when the bolt is withdrawn. The bracket 184 does not move back outwardly with the bolt 116 since the length of the slot 124 is sufficient to allow the bracket 184 to maintain its innermost position. By turning the lock arm to the locked position, the key 166 may then be taken by the customer that has just deposited the cleaning in the receptacle through the opening formed by

the closure member and, of course, the customer closes the closure member by raising the same. No one else can have access to the locker since no one else's key will fit. The serviceman then comes and opens the device by removing the top lid and pressing on the latch in an obvious manner. When he does this, he also removes the coin from the coin receiving means and sets the slide 82 to the desired number of quarters and also sets the disk 212. It may be added that when the lock arm 168 was moved to the locked position, the L-shaped member 220 was moved laterally so that the vacant portion was no longer visible and only the quarters indicia was visible. As illustrated in FIGURE 7, the device is set up for receiving one quarter when the customer returns for his cleaned garment thus making two quarters total for the cleaning. The serviceman will remove the garment along with the lock plate 160 and assemble the lock plate with the garment on the hanger and the entire assembly will go to the cleaning plant. This enables the serviceman to use the same locker several times during the period of cleaning since it is only necessary for him to insert another lock plate to put the locker back into service. When the serviceman brings the cleaned garment back, he places it in a locker which may be one that he has just removed soiled garments from and places the lock plate back into the front plate 24. He then sets the disk 212 and sets the slide mechanism 82 correspondingly and also sets the bracket 184 with the tongue 186 engaged with the hook shaped end 104 of the latch 196 as illustrated in FIGURE 12. The customer after matching his key with the lock will insert the indicated number of coins and when the proper number of coins have been inserted as well as the key which allows the lock arm to swing up, the bolt 116 may be pushed inwardly since the abutment 144 will engage a coin rendering the arm 140 swingable rearwardly so that the abutment 146 will engage the face of the projection 148 facing the front wall thus allowing continued movement of the bolt 116 inwardly. During the initial movement of the bolt 116 inwardly, the cam 128 will engage the projection 202 thus lowering the hook shaped end 204 and releasing the tongue 186 so that it is spring biased back to a position alongside of the slide 114 with the pin 192 engaging the bolt 116 outwardly of the slot 124 thereby leaving the bracket 184 overlying notch 172 thus preventing subsequent removal of the key. When the lock arm swings back to a vertical position, the pin 182 engages the indicator and flips it over so that the vacant sign is once more revealed and indicating that the device is again ready for use. Of course, when the lock bolt was pushed in the closure door was released and the person obtained his cleaned garments and closed the closure member. The coins which were dropped in by the customer when he retrieved his cleaned garments also were dropped down the distance of one quarter or whatever distance determined by the construction of the slide which in this instance is constructed to allow the coins to move down a distance equal to the diameter of a single quarter, by release of the coin release lever when the bolt 116 was pushed inwardly.

In order to prevent sliding movement of the bracket 184 on the guide 114 by tilting and shaking the entire device which would enable removal of the key without depositing a coin, there is provided a bracket 236 rigid with the guide 114 and including a bowed leaf spring 232 which will engage the tongue 186 and stop the bracket 184 before it slides beyond the notch 172 in the guide 114.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. In a coin and key lock mechanism, a housing, an elongated guide extending through a wall of said housing, a slide bolt reciprocally mounted in said guide, a latch mechanism mounted on the housing and including a portion thereof disposed in the path of movement of the inner end of the slide bolt for actuation when the slide bolt is moved inwardly, key operated lock means mounted on the housing and engaging the bolt inwardly of the housing for selectively preventing inward movement of the bolt, coin receiving means disposed within said housing, and a latch arm mounted on the bolt for preventing inward movement of the bolt in the absence of a coin in the coin receiving means, said latch arm having an abutment thereon for engagement with a coin in the coin receiving means for pivoting the latch arm to a position enabling inward movement of the bolt to engage the latch mechanism disposed within the housing, said guide and bolt including alignable notches, and sliding means mounted on the guide and disposed in overlying relation to the notch in the guide thereby preventing engagement of a lock arm forming part of the lock means with the notches and preventing removal of the key from the lock means until after the bolt has been initially pushed in after deposit of an initial coin, and means interconnecting the sliding means and bolt to move the sliding means inwardly with the bolt for permitting removal of the key after the bolt has been pushed inwardly initially and returned to an outer position whereby the lock arm may engage the notches.

2. The combination as defined in claim 1 wherein means is mounted on the guide member to retain the sliding means in its inner position to prevent the sliding means from being moved back to its outer position by the force of gravity thereby requiring a manual resetting of the sliding means.

3. The combination of claim 1 wherein said sliding means includes a bracket longitudinally slidably mounted on said guide, a tongue pivotally mounted on said bracket and extending alongside of the guide, spring means biasing said tongue towards said guide, a pin on said tongue projecting towards the guide when the tongue is disposed alongside of the guide, said guide having a slot receiving said pin and enabling movement of said bracket in relation to the guide when the pin is disposed in the slot, said bolt having a longitudinal groove therein receiving said pin when said pin extends through the slot and the groove is aligned therewith, latch means carried by said housing and releasably retaining the tongue in outwardly extending relation to the guide whereby the pin is out of engagement with the slot and groove, said latch means being manually engaged with said tongue, and cam means on the bolt to release said latch means in response to longitudinal movement of the bolt, said groove having an outer end for engaging the pin during inward movement of the bolt thereby moving the bracket inwardly with the bolt into overlying relation to the notches in the guide and bolt to prevent entry of the lock arm into the notches when the bracket overlies the notches, said pin and tongue constituting the means interconnecting the sliding means and bolt.

4. The structure as defined in claim 3 wherein means is provided on the guide engageable with the tongue when in the innermost position thereby retaining the bracket in its innermost position so that it cannot be moved back to an outer position by gravity.

5. The structure as defined in claim 4 wherein said key operated lock means including a mounting plate, said housing having a slot-like opening communicating with one edge thereof and slidably receiving said mounting plate whereby the mounting plate, lock means and lock arm may be removed from the housing and retained with the garment and another lock means inserted into the housing.

6. The structure as defined in claim 5 wherein said coin receiving means includes a vertically disposed member

having spaced parallel vertical strip members, said strip members having grooves in the inner edges thereof for receiving diametrically opposed edges of the coin thus disposing the coin in a substantially vertical position, means on said strip members for limiting the number of coins insertable into the coin receiving means, said means on the strip members being vertically adjustable for varying the number of coins receivable, coin release means supported on the strip members for movement to a coin releasing position in response to complete inward movement of the slide bolt thus enabling the coins to drop downwardly for subsequent collection when the bolt is moved completely inwardly to operate the latch mechanism.

7. The structure as defined in claim 6 wherein said key operated lock means includes spring means urging the lock arm to a position out of engagement with the notches in the bolt and guide, a laterally projecting pin carried by said lock arm, said housing including an indicating means having a sliding element with portions thereof having indicia thereon for selective viewing through a window in the housing, a rotatable disk having numerical indicia thereon for indicating the number of coins, said disk being manually rotatable from the interior of the housing and being observable through a window, said sliding element having a recess engageable by said pin on the lock arm for movement in response to swinging movement of the lock arm.

8. The structure as defined in claim 7 wherein said coin receiving means includes a projection thereon, said latch arm being engageable with said projection in the 30

absence of a coin in the coin receiving means thereby preventing complete inward movement of the slide bolt in relation to the guide and latch mechanism.

9. The structure as defined in claim 8 wherein said coin receiving means is removably suspended from said housing, said strip members having the grooves extending throughout the length thereof and being elongated for purposes of receiving a number of coins therein whereby removal of the coin receiving means will also remove the coins for access thereto.
